(57) **CLAIM**

The ornamental design for a cable gland, as shown and described.

DESCRIPTION

1.-3. Cable gland

1.1 is a front perspective view of my new design for cable gland,

1.2 is a rear perspective view thereof,

1.3 is a left side view thereof,

1.4 is a right side view thereof,

1.5 is a top view thereof,

1.6 is a bottom view thereof,

2.1 is a front perspective view of an alternate embodiment,

2.2 is a rear perspective view thereof,

2.3 is a left side view thereof,

2.4 is a right side view thereof,

2.5 is a top view thereof,

2.6 is a bottom view thereof,

3.1 is a front perspective view of another alternate embodiment,

3.2 is a rear perspective view thereof,

3.3 is a left side view thereof,

3.4 is a right side view thereof,

3.5 is a top view thereof, and

3.6 is a bottom view thereof.

The broken line showing in figures 1.1 through 3.6 is for the purpose of illustrating environment and forms no part of the claimed design.
